DEVICE FOR STRETCHING THE ROOF OF A TENT

Filed Feb. 11, 1922

UNITED STATES PATENT OFFICE.

PETER C. SCHAEFER, OF DENVER, COLORADO.

DEVICE FOR STRETCHING THE ROOF OF A TENT.

Application filed February 11, 1922. Serial No. 535,819.

To all whom it may concern:

Be it known that I, PETER C. SCHAEFER, a citizen of the United States, residing at Denver, in the county of Denver and State 5 of Colorado, have invented certain new and useful Improvements in Devices for Stretching the Roof of a Tent, of which the following is a specification, reference being had therein to the accompanying drawings.

10 This invention relates to a device for stretching the roof of a tent, and the object of the invention is the provision of a simple and efficient stretcher frame which can be quickly placed in position, and which 15 will efficiently stretch the top of a tent.

With this and other objects in view, my invention comprises certain novel combinations, constructions and arrangements of parts as will be hereinafter described, illustrated in the accompanying drawings, and more particularly pointed out in the appended claim.

In the drawings:

Figure 1 is a view of a tent with my device therein, for stretching the top of the tent, the tent being shown in conjunction with an automobile, as the tent with the stretcher device is admirably adapted for the use of campers or tourists, or the like.

30 Figure 2 is a perspective view of the stretcher frame.

Figure 3 is a fragmentary view of the tent and frame, showing particularly the pockets of the tent for supporting the stretcher frame.

Referring to the drawings by numerals, 1 designates the tent and 2 roof thereof; 3 is a suitable flap or connection for assisting in closing the space between the tent and the 40 automobile 4. Attached to the upper portion of the tent 1, and inside thereof, near the roof 2, are, preferably, four horizontal pockets 5, open at their ends, contiguous to the corners of the roof 2, and in each pocket 45 5 is removably positioned an eye-bar 6 or a pin-bar 7, as the operator desires.

The stretcher frame comprises, preferably, two eye-bars 6 and two pin-bars 7. Threaded on the ends of each eye-bar 6 are caps 8 having integral eyes 9. Threaded on the 50 ends of each pin-bar 7 are caps 10 having

integral pins 11. The pins 11 extend through the eyes 9 when the stretcher frame is assembled, as shown in dotted lines "A" in Fig. 1, and in full lines in Fig. 2.

Each corner of the tent is, preferably, reinforced by a relatively small strip 12 (Fig. 3) which strip or piece is usually engaged by the eye and pin structure of the stretcher frame.

A tent pole 13 is employed for supporting the tent in an erected position, whereas, my stretcher frame efficiently stretches the roof structure of the tent to hold the tent in proper shape.

I find, from practical experience, that my device is easy to operate, and is efficient in operation.

It is to be noted that the ends of all the bars are so constructed that they constitute 70 an interlocking means as the pin-bars interlock into the eye-bars.

While I have described the preferred embodiment of my invention, and have illustrated the same in the accompanying 75 drawings, certain minor changes or alterations may appear to one skilled in the art to which this invention relates, during the extensive manufacture of the same and I, therefore, reserve the right to make such 80 alterations or changes as shall fairly fall within the scope of the appended claim.

What I claim is:

In a structure of the character described, the combination of a tent provided with side 85 walls and a roof and strips about the tent and providing pockets at the junction of the side walls and roof, and a stretcher frame comprising bars in said pockets having their ends extended beyond the ends of the pockets at the corners of the side walls, caps in threaded engagement with the ends of certain of said bars and their outer ends provided with eyes, and caps in threaded engagement with the ends of the remaining 95 bars having their outer ends provided with pin extensions fitting into the eyes of the first bars to releasably connect the bars in frame forming relation to each other.

In testimony whereof I hereunto affix my 100 signature.

PETER C. SCHAEFER.
